UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

METHOD OF MAKING SHOES.

1,120,672.

Specification of Letters Patent. Patented Dec. 15, 1914.

Application filed September 3, 1907. Serial No. 391,089.

To all whom it may concern:

Be it known that I, ARTHUR BATES, a subject of the King of England, residing at Leicester, in the county of Leicester, England, have invented certain Improvements in Methods of Making Shoes, of which the following description, in connection with the accompanying drawings, is a specification, like reference characters on the drawings indicating like parts in the several figures.

This invention relates to the manufacture of boots and shoes and particularly to a method of making shoes having outturned uppers. In such shoes, which are called "stitch down" shoes or veldtschoen, the outturned flange of the upper lies upon and is secured to the upper face of the projecting edge portion of the sole.

In accordance with this invention a stitch down shoe is made by assembling upon a last or form an upper and a sole which is larger than the bottom of the last so that it projects beyond the sides of the last. The upper is pulled over the last or otherwise manipulated as may be necessary or desirable to cause it to fit to the last, during which operation it may conveniently be drawn over the edge of the sole. Then while the upper is still held under pulling or other tension produced in the overworking operation it is retracted or drawn back from the position to which its edge was pulled, to produce the slack or fullness that will be required to allow the upper to fit into the angle formed by the side of the last and the projecting edge of the sole. The slack or fullness for this purpose may, however, be obtained by any appropriate manipulation of the stock. Advantageously a measured amount of slack or fullness is produced and this will preferably be obtained by forcing the upper into the said angle where it may be caused to assume approximately the position against the side of the last and upon the upper face of the projecting portion of the sole which it will occupy in the finished shoe, or as it may be expressed, the upper is made to "line" the

angle or lay as a covering over the inner face of the angle between the side of the last and the projecting portion of the sole. This has the advantage also of bending or initially forming the upper to the shape it will

finally occupy. After the slack or fullness which will be required is obtained the upper will be fastened to secure it in its proper position or adjustment. This may be advantageously effected by driving tacks through the upper into the edge of the sole but can also be done by sewing through the upper and the margin of the sole. The operation of pulling the upper, pressing it into or otherwise substantially lining the angle to obtain the fullness required and fastening the upper to the sole may and preferably will be performed step by step on successive portions of the upper progressively until the upper has been lasted and tacked all the way around.

If the upper is to be tacked to the edge of the sole there is a serious problem involved if the sole is a light one because it presents a thin body into which to insert a tack in such position that it will hold, and the fact that the edge of the sole is covered and hidden by the upper at the time the tack is driven renders it particularly difficult to drive the tacks accurately in uniform holding position. For the best results when fastening by tacks, therefore, the projecting edge portion of the sole will be positioned in a definite location for the tack driving operation and preferably the projecting edge portion of the sole will be clamped upon its opposite, or tread and top, faces. Conveniently the upper on the top face of the sole will be clamped with said edge portion of the sole, and this may be effected by the tool which shapes the upper into the angle formed by the side of the last and the projecting edge portion of the sole. Said tool may be the movable member of the clamp and coöperate with a fixed work-rest engaging the tread face of the sole. For performing its functions in the specific procedure herein illustrated said tool may advantageously be advanced toward the plane of the sole yieldingly to permit of variations in the thickness of the stock, and then be forced toward the side of the last to bend the upper into said angle, causing the upper substantially to line said angle, and then hold the work while the tack is driven. Clamping the stock as described has the advantage, in addition to positioning or locating the edge portion of the sole, that it supports the sole to enable it to receive the

- 2
- thrust of the ingoing tack and makes it possible to drive a tack into the edge of stock which is so flexible, soft or thin that it would crumple or bend during the tack driving operation if it were not supported.
- 5 It will be recognized that, in a broad aspect, this invention consists in positioning an upper over a last and a sole which projects beyond the end of the last, supporting the tread face of the projecting portion of 10 the sole, tucking the upper into the angle between the side of the last and the sole, and clamping it against the supported portion of the sole, and fastening the upper 15 while it is tucked into said angle, all as successive steps in a continuous operation. The tucking may be done by rubbing pressure applied downwardly along the upper which is to line one side of the said angle.
- 20 For purpose of explaining this improvement in the methods of making shoes an apparatus is herein shown which may be employed in practising the invention, although it should be understood that the 25 invention is not limited to use with a particular apparatus or with any apparatus as it may be practised with the handle or with the hand tools. The apparatus shown in the drawings is not herein claimed as it is comprised in the subject matter of United States Letters Patent, No. 1,002,358, granted September 5, 1911, on application filed by me 30 September 3, 1907; Serial No. 391,088.
- Figure 1 shows a shoe in operative position with relation to one form of devices 35 by which it may be operated upon. Fig. 2 shows the upper gripped and pulled. Fig. 3 shows the upper drawn over the edge of the sole. Fig. 4 shows a pressing device advanced to engage the upper. Fig. 5 shows a 40 presser forcing the upper into the angle formed by the side of the last and a sole projecting beyond the edge of the last bottom, the upper lining the angle and being 45 in condition to be fastened to the sole. Fig. 6 shows the presser holding the upper while the upper is being fastened by a tack driven through the upper into the edge of the sole.
- 50 The apparatus which is illustrated merely for the purpose of aiding me in describing my invention comprises a pair of grippers 2 which are actuated by suitable mechanism for closing to grip the upper, rising to pull 55 the upper for conforming it to the contour of the portions of the last with which it engages, and for overdrawing the upper across the edge of the sole and holding it under tension. An abutment or rest 4 is provided 60 which engages the tread face of the portion of the sole projecting beyond the edge of the last bottom and preferably also engages the edge face of the sole. A tack block 6 is reciprocated by suitable mechanism for- 65 wardly and backwardly in a horizontal

plane moving from the position shown in Fig. 1 to the position shown in Fig. 6, in which movement it carries a tack between the driver 8 and the edge of the sole. A presser 10 is mounted for turning and sliding movement upon a shaft 12, the presser being slotted at 14 for this purpose. A spring 15 extends from a stud 16 on the presser to a stud 18 on the tack block and is so arranged with relation to the shaft 12 70 that it holds the presser normally in the raised position shown in Fig. 1 and urges the presser forward toward the shoe. The presser, which is shown in the form of an open frame, is provided on its side members 80 with a shoulder 20 which the spring 15 holds against the stud 18. The side members of the presser are also provided with inclined or cam faces 22 which are engaged by the stud 18 during the forward movement of the tack block to rock the presser downwardly from the position shown in Fig. 4 to the position shown in Fig. 5. The driver is connected with suitable actuating mechanism by which it is impelled downwardly for driving the tack from the tack block into the work, as shown in Fig. 6.

In practising this method with the apparatus above described the work, comprising a last with an upper and a sole which projects beyond the edge of the last bottom, is presented in the position shown in Fig. 1 with the tread face of the sole and the edge of the sole against the rest or abutment 95 4. The grippers first close upon the upper and pull it to stretch it about the last into conformity with the surfaces of the last over which the upper is drawn. In this pulling movement the upper is preferably stretched without drawing it across the 100 edge of the sole and the grippers are subsequently given an outward movement to lay the upper over the edge of the sole. The tack block then advances and as it does so permits the spring 15 to advance the presser 105 against the upper, which it engages adjacent to the edge of the sole. As the advance movement of the presser is checked by its engagement with the upper the tack block moves forwardly with relation to the 110 presser and, riding over the inclined face 22, rocks the presser downwardly against the upper, causing it to force the upper into the angle formed by the side of the last and the projecting portion of the sole, as shown 115 in Fig. 5. In this downward movement of the presser it preferably draws the upper from the direction of the grippers to obtain the stock necessary to extend into said angle. After the presser has forced the upper into the angle the tack driving mechanism is actuated to fasten the upper by a tack which is driven through the upper and into the edge of the sole, as shown in Fig. 6. 120 It is of course, not essential to the broad as- 125 130

pect of the invention that the presser have the described movements in causing the upper to line the angle between the side of the last and the edge base of the sole, nor is it 5 essential that the upper be fastened first by tacks preparatory to sewing it to the top face of the sole at or close to said angle. In this operation the upper is pulled to cause it to conform to the last as it should do in a 10 lasted shoe, and sufficient slack is then provided by the operation of the presser to enable the upper to extend into the angle between the side of the last and the sole and line the angle as it must do in the completed 15 shoe in which the upper is secured to the top face of the sole at or close to said angle. The tacks hold the upper in its correct relation to the last until in a subsequent operation the upper is permanently attached to 20 the sole, as for example, by the usual sewing machine which forms the upper between the tacks and the last into the angle between the side of the last and the projecting margin of the sole, thus reestablishing substantially 25 the tension originally produced by the grippers, and there sews it to the projecting margin of the sole. The present method, carried out in all the details herein suggested, has the important advantage that 30 each portion of the upper is drawn back, after being tensioned, the amount which is necessary to allow it to be formed into the angle so that each portion of the upper will be permanently fastened in the angle by the 35 sewing machine or otherwise under substantially its original lasting tension, which can be reestablished with certainty by the described procedure.

Having explained the nature of this invention and fully described how it may be practised, I claim as new and desire to secure by Letters Patent of the United States:—

1. That improvement in methods of lasting shoes progressively by repeated cycles of operations on successive portions of the shoe, each cycle consisting of tightening a small section of the upper over the last and holding its edge outwardly therefrom under 45 yielding tension and unsecured to the sole, then while maintaining the tension, drawing back the tightened upper against the yielding tension to produce slack; and then fastening the edge of the treated portion of 50 the upper to the sole.

2. That improvement in methods of making stitch-down shoes which consists in first tightening a small section of an upper over a last by pulling its edge away from the 55 last; and, while maintaining the tightened section under tension and free for movement relatively to the sole, drawing back from said edge toward the last enough stock to extend into and substantially line the angle 60 between the side of the last and the top face

of the projecting margin of the sole; then fastening the upper, all as successive steps in a continuous cycle; and repeating all the steps of the cycle upon each successive portion of the upper to last the shoe progressively as described. 70

3. That improvement in methods of making shoes which consists in tightening a section of an upper over a last carrying on its bottom face a sole which projects beyond the side of the last; and, before fastening the upper, subjecting the tightened section to pressure at the angle between the sole and upper to produce, by drawing back the upper from the direction of pull, the stock 75 needed to extend into and substantially line that angle in the completed shoe; and then fastening the upper. 80

4. That improvement in methods of making shoes which consists in positioning an upper over a last carrying on its bottom face a sole which projects beyond the side of the last; pressing the upper against the top face of the projecting portion of the sole to form an outturned flange; and forcing the upper, 85 by rubbing pressure applied over said flange, toward the side of the last in a plane agreeing with the plane of said flange. 90

5. That improvement in methods of making shoes which consists in pulling an upper over a last carrying a sole which projects beyond the edge of the last and, while holding the upper about the last under tension and before fastening it, pressing the upper as an intermediate step against the top face 95 of the projecting portion of the sole and against the side face of the last adjacent to its edge to form an outturned flange of the upper fitted to the last and substantially line the angle between the sole and the last; and 100 then fastening the upper while it is so pressed into the angle between the said two faces. 105

6. That improvement in methods of making shoes which consists in positioning an upper over a last having a sole projecting beyond the edge of the last; supporting the tread face of the projecting marginal portion of the sole; then beginning to press the upper against the top face of the marginal portion of the sole and extending the area of pressure progressively from the edge of the sole toward and approximately to the edge of the last without correspondingly changing the area of the sole being supported, and securing the upper to the marginal portion of the sole. 110 115 120

7. That improvement in methods of making shoes which consists in positioning an upper over a last and a sole which projects 125 beyond the edge of the last, supporting the tread face of the projecting portion of the sole, tucking the upper into the angle between the side of the last and the sole and clamping it against the supported portion 130

of the sole and fastening the upper while it is tucked into said angle, all as successive steps in a continuous operation.

8. That improvement in methods of making shoes which consists in repeating upon successive portions of the upper a full cycle of steps which includes tensioning the upper outwardly from the last and a sole projecting beyond the edge of the last; then while maintaining the upper under tension about the last pressing the upper into the angle between the side of the last and the top face of the projecting margin of the sole into the position it is to occupy in the finished shoe; and then driving a tack through the upper into the edge of the sole.

9. That improvement in methods of making shoes with uppers having outturned sole attaching flanges which consists in proceeding step-by-step about the shoe by tightening successive sections of the upper over a last, additionally forming each section into the angle between the side of the last and a projecting edge of the sole by pressure directed inwardly across the flange toward the last while the tension is maintained to define sharply the position which the upper is to assume in the finished shoe, and securing the flange to the sole.

10. That improvement in methods of making shoes having uppers with outturned sole attaching flanges which consists in tensioning the upper over a last; then, while the tension is maintained, drawing back the upper and pressing it into the angle formed by the side of the last and the projecting edge of the sole; then temporarily securing the upper to the sole edge; then releasing the pressure; then forming the upper into the angle again and in so doing restoring approximately the original degree of tension; and sewing or otherwise permanently fastening the upper to the top face of the sole while the upper is under substantially the original degree of tension.

11. That improvement in methods of making a stitch-down shoe which consists in seizing and holding a portion of the margin of the upper at a point beyond the edge of the last, forcing the upper into the angle between the side of the last and the projecting margin of the sole to line the said angle with the upper stock, securing the portion so acted upon to the sole, and repeating the operation progressively by seizing and holding, forcing into the angle and securing successive portions of the margin of the upper along the edge of the shoe.

12. That improvement in method of making stitch-down shoes which consists in gripping and pulling a portion of upper over the last, reversely moving the edge portion of the upper to produce a predetermined amount of slack between the portion tightly drawn to the last and the portion gripped

for pulling, and securing the upper to the edge of the sole to maintain the predetermined amount of slack thus produced and required for the subsequent sewing operation.

13. That improvement in method of making stitch-down shoes which consists in moving successive portions of the marginal edge of the upper through varying distances determined by the varying elasticity of the stock, reversely moving said marginal portions distances determined by the depth of the angle between the side of the last and the projecting margin of the sole without releasing the tension upon the portion of upper in contact with the side of the last, and thereafter securing the upper to the margin of the sole.

14. That improvement in method of making stitch-down shoes which consists in moving portions of the marginal edge of the upper through varying distances which are determined by the elasticity of the upper stock by subjecting it to a uniform tensioning force, drawing back from the marginal edge sufficient stock to line the walls of the crease between the side of the last and the projecting margin of the sole, and securing the upper to the sole to maintain the slack produced by the backdrawing operation.

15. That improvement in method of making stitch-down shoes which consists in applying a predetermined uniform tension to successive portions of the upper to adapt it to the configuration of the adjacent side of the last while it is bridged across the crease between the side of the last and the top face of the projecting margin of the sole, drawing back an amount of stock from each tensioned marginal portion of the upper predetermined by the depth of the crease while the upper is still under the said uniform tension, and then securing the upper to the projecting margin of the sole.

16. That improvement in methods of making shoes which consists in repeating upon successive portions of an upper applied over a last and a sole projecting beyond the edge of a last a full cycle of steps which include engaging the edge of the upper outside the edge of the last bottom, forcing the upper into the angle to substantially line the angle between the side of the last and the projecting edge of the sole, applying clamping pressure to the portion of the upper lining the sole face of said angle, and fastening the upper to the sole while the upper is held in position to line said angle.

17. That improvement in methods of making stitch-down shoes which consists in repeating upon successive portions of an upper applied over a last and a sole projecting beyond the edge of a last a full cycle of steps which include forcing the upper by rubbing pressure applied against the one

face of the angle between the side of the last and the projecting face of the sole to form an out-turned flange of the upper and substantially to line said angle, and then fastening the upper to the sole while it lines said angle.

In testimony whereof I have signed my

name to this specification in the presence of two subscribing witnesses.

ARTHUR BATES.

Witnesses:

ARTHUR ERNEST JERRAN,
JOHN RICHARD LAW.

It is hereby certified that in Letters Patent No. 1,120,672, granted December 15, 1914, upon the application of Arthur Bates, of Leicester, England, for an improvement in "Methods of Making Shoes," an error appears in the printed specification requiring correction as follows: Page 2, line 27, for the word "handle" read *hands*; and that the said Letters Patent should be read with this correction therein that the same may conform to the record of the case in the Patent Office.

Signed and sealed this 16th day of February, A. D., 1915.

[SEAL.]

J. T. NEWTON,

Acting Commissioner of Patents.
